RECOVERY OF TETRAALKYL LEAD FROM ELECTROLYTIC REACTION MIXTURES

Jack Linsk, Highland, and Ralph W. Carl, Hammond, Ind., and Edmund Field, Chicago, Ill., assignors to Standard Oil Company, Chicago, Ill., a corporation of Indiana

Filed Dec. 30, 1960, Ser. No. 79,845

7 Claims. (Cl. 204—59)

This invention relates to organometallic compounds, and more particularly concerns an improved electrolytic process for making tetraalkyl lead compound.

Tetraalkyl lead compounds such as tetraethyl and tetramethyl lead are commercially important organometallic compounds. It has heretofore been discovered that tetraalkyl lead compounds such as these may be prepared by electrolyzing the corresponding alkyl Grignard reagent, e.g., ethyl magnesium chloride, using a lead anode. By this process, alkyl groups in the Grignard reagent are transferred to the anode, forming tetraalkyl lead and giving magnesium chloride as a by-product. This electrolytic process is materially superior to the conventional sodium-lead process by reason of its lower capital, raw material, and operating expenses.

It has also been discovered that the solvent used in the electrolysis controls, to a large extent, the practical success of the process. At present, a mixture of certain high boiling ethers with lower boiling tetrahydrofuran, a normally liquid aromatic hydrocarbon such as benzene, and excess alkyl halide constitute the solvent of choice. Grignard reagents in this mixture possess high electrical conductivity, which thus reduces I^2R losses and makes for high overall electrical efficiency. In addition, the solvent mixture maintains its fluidity and solvent capacity for the various reactants and products during all stages of the electrolysis. Moreover, the presence of excess alkyl halide avoids undesirable gassing and provides an electrical efficiency substantially in excess of the theoretical four Faradays per mol of product.

However, by its very complexity, mixed alkyl halide-ether-tetrahydrofuran-aromatic solvents present difficulties with respect to recovering the tetraalkyl lead product and the various solvent components in a form suitable for reuse. Distillation alone, for example, is not satisfactory inasmuch as the high temperatures necessary to separate tetraalkyl lead from high boiling ethers result in chemical attack of the expensive ethers by residual Grignard reagent. Prior decomposition of the Grignard reagent by hydrolysis is not always the solution since, in that case, overhead products will be contaminated with water. Accordingly, the major object of this invention is to provide a process for recovering tetraalkyl lead and solvent components from the aforementioned electrolytic reaction by a procedure which combines the simplicity of distillation with the solvent-conserving features of hydrolysis. At the same time, Grignard attack on the ether is virtually completely prevented, and most of the solvent can be recovered in a dry form suitable for reuse.

In accordance with the invention, tetraalkyl lead is first manufactured by now-conventional electrolytic procedures, utilizing a lead anode and a solution of alkyl Grignard reagent in a solvent comprising excess alkyl halide, a high boiling ether, tetrahydrofuran, and an aromatic hydrocarbon. After electrolysis has proceeded to an extent where a substantial amount of alkyl Grignard reagent is converted to tetraalkyl lead, the electrolytic reaction mixture is subjected to a first low-temperature distillation. To avoid mechanical problems it may be advantageous to recycle a portion of the dry, high boiling ether to this distillation step. The distillation overhead, containing alkyl halide, tetrahydrofuran, and aromatic

2

hydrocarbon is withdrawn; this is completely dry and is suitable for recycle to alkyl Grignard preparation. The bottoms from this distillation, containing tetraalkyl lead products, unreacted Grignard reagent, magnesium halide by-product, and high boiling ether, is hydrolyzed with aqueous hydrochloric acid to decompose the Grignard.

Hydrolysis produces two liquid phases. The aqueous phase is chiefly composed of magnesium halide, while the organic phase contains tetraalkyl lead and high boiling ether, possibly with a portion of unremoved aromatic hydrocarbon.

This organic phase is then redistilled either at sub-atmospheric pressure or in the presence of steam to separate a tetraalkyl lead overhead from the high boiling ether bottoms. If this distillation employs steam, the ether may be dried by redistillation and then returned to electrolysis, while if subatmospheric pressure distillation is employed the bottoms per se are suitable for recycle. The overhead from this distillation is tetraalkyl lead product, possibly containing a small amount of aromatic hydrocarbon, and may then be withdrawn as the final product of the inventive process.

The invention in its various aspects will be more fully described and more clearly understood from the ensuing specification, which is to be read in conjunction with the attached single drawing showing, in schematic form, a flowsheet exemplifying the principles of this invention. For sake of clarity and simplicity of presentation, many auxiliaries and utilities have been omitted from the drawing, but those skilled in the art will readily perceive the need for and appreciate the location of such items as pumps, gauges, duplicate items of equipment, distillation tower auxiliaries, etc.

Before discussing the flowsheet however, it is of advantage to clarify certain aspects of the electrolytic process. Essentially, two mols of alkyl Grignard reagent, two mols of alkyl halide, and 1 of metallic lead are converted to 1 mol of tetraalkyl lead and two mols of by-product magnesium dihalide, the electrolysis requires a solvent for the Grignard reagent, and this is optimally a solution of excess alkyl halide, a high boiling ether, tetrahydrofuran, and a normally liquid aromatic hydrocarbon.

The high boiling ether may be any ether boiling above the boiling point of the particular tetraalkyl lead compound being manufactured. Of the many ethers which may be used, those which are dialkyl ethers of an ethylene glycol, having at least two carbon atoms in each alkyl group and not more than two ethylene groups in the glycol portion, are preferred, since the resultant electrolyte is able to preserve its homogeneity over a wide range of concentrations and temperatures. Thus, exemplary glycol ethers are the diethyl ether of ethylene glycol, the dibutyl ether of ethylene glycol, the diethyl ether of diethylene glycol, the dibutyl ether of diethylene glycol, and the hexylethyl ether of diethylene glycol. Ethers other than those within the foregoing preferred class may also be used, and as examples of these there may be mentioned the dimethyl ether of diethylene glycol, the dimethyl ether of triethylene glycol, and various cyclic ethers, keeping in mind that the ether should boil higher than the tetraalkyl lead product (tetramethyl lead boils at 120° C. and tetraethyl lead boils at about 195° C. with decomposition).

Aromatic hydrocarbons as components of the electrolyte may be any of the aromatics which are liquid at room temperature and which are inert to Grignard reagents under conditions of the electrolysis. Benzene and the alkyl benzenes such as toluene, the xylenes, cumene, the cymenes, etc. may be used, although it has been found that the simpler alkyl benzenes having only methyl groups offer some advantages with respect to low boiling points and high stability.

The overall electrolyte composition may be varied over wide ranges, depending upon desiderata of chemistry and economics. The alkyl Grignard reagent is advantageously employed at a concentration within the range of about 1.5 to about 3.5 Normal, preferably within the range of about 2 to about 2.5 Normal at the start of electrolysis. Enough high boiling ether and tetrahydrofuran (which, of course, is an ether) should be used so that approximately one mol of ether is available for each molecule of magnesium chloride formed in the electrolysis. High boiling ether may thus be employed at a concentration of from about 10 to about 90%, more or less, by weight of solution, while tetrahydrofuran may suitably be used at a concentration between about 2 and 60% or more by weight. The aromatic hydrocarbon can vary over a broad range, with as little as 2 or 3 weight percent offering substantial advantages which are even further increased by using concentrations of as high as 50 weight percent or more. Alkyl halide concentrations of, say, 1-50 weight percent of total electrolyte should also be used, since excess alkyl halide materially improves electrolyte conductivity and reduces the formation of by-product gases.

It appears that the optimum electrolyte composition prior to electrolysis is an alkyl Grignard concentration of about 1.5-3.5 Normal, a high boiling ether concentration of about 40-80%, about 10-40% tetrahydrofuran, about 30-50 weight percent aromatic, and about 1-10 weight percent excess alkyl halide.

The alkyl Grignard reagents are chosen to produce the desired tetraalkyl lead product. For example, an ethyl Grignard will afford tetraethyl lead, while a methyl Grignard will yield tetramethyl lead. Alkyl lead compounds having from 1 to about 4 carbon atoms per alkyl group are most effectively produced by the electrolytic process. By employing mixed Grignard reagents, such as a mixture of ethyl Grignard and methyl Grignard, or a mixture of ethyl Grignard with methyl halide, a mixed tetraalkyl lead compound may be prepared; thus, dimethyl diethyl lead can be produced readily. The halide portion of the alkyl Grignard reagent may be the chloride, bromide, or less, desirably, the iodide.

Conditions in a typical electrolytic cell advantageously include a temperature within the range of about 20° C. to about 100° C., preferably about 20-50° C., and optimally about 25-35° C. A current density, at both the anode and cathode, within the range of about 0.2 to about 100 amperes per square foot is advantageously employed. Relatively low voltages, of the order of about 20-30 volts, are preferred, although cell voltages of 50 volts and even higher may be utilized. Cell pressures may range from atmospheric to low superatmospheric, say 60 p.s.i.g., but are preferably lower, i.e. less than about 30 p.s.i.g. The electrolysis is advantageously continued, in either a batchwise or continuous process, until a substantial amount of the Grignard reagent is converted to tetraalkyl lead, and advantageously is conducted until at least a major amount, and preferably at least about 80% of the Grignard reagent is so converted.

Turning now to the drawing, Grignard reagent is prepared in preparation zone 11 for the ultimate preparation of tetramethyl lead. Methyl chloride is admitted from source 12 via line 13, while magnesium metal chips are charged from symbolic source 14 and line 16 to the preparation zone. Recycle ether, in this case hexylethyl ether of diethylene glycol, is recycled via line 17, while recycle methyl chloride and tetrahydrofuran are introduced through line 18. Make-up solvent components, e.g., benzene, tetrahydrofuran, and ether, are charged as needed through line 19. Grignard solution from preparation zone 11 is 1.98 molar with respect to methyl Grignard and has an approximate composition of 3638 parts by weight of alkyl Grignard reagent in hexylethyl ether of diethylene glycol, 1307 parts of benzene, 131 parts of tetrahydrofuran, and 103 parts of methyl chloride. (An

additional 347 parts of methyl chloride is added to cell 22 during the run.) It is charged via line 21 to electrolytic cell 22, which is provided with lead anodes 23 and stainless steel cathodes 24 connected to a direct current power supply 26. Electrolysis is commenced and temperature is maintained at 36-41° C. by recirculation of electrolyte through an external heat exchanger, not shown. Electrolysis is commenced with an initial plate voltage of 17.5 and an amperage of 19.0, which voltage is progressively increased during the run to a maximum of 40.4 volts at the termination, 11 hours. The average voltage is 24.9, while the average temperature is 41.1° C. and pressure is 3.1 p.s.i.g. Grignard conversion is 95.3%, of which 99.1% is traceable to tetramethyl lead. The current efficiency is 158% of theoretical, and the power required is 2.86 kilowatt hours per pound of tetramethyl lead.

After the 11 hours of electrolysis, the reacton mixture is withdrawn via line 27 and conducted to subatmospheric pressure distillation tower 28. This tower, advantageously operating at a pressure below about 500 millimeters' mercury absolute and a pot temperature below about 110° C., and having, say, 5-20 theoretical plates and a reflux ratio of about 5-20 reflux-to-product, separates an overhead containing substantially all of the unreacted excess alkyl halide, substantially all of the tetrahydrofuran, and at least a major portion of the benzene from a bottoms containing substantially all of the tetramethyl lead, unreacted Grignard reagent, magnesium chloride, a minor amount of the benzene, and hexylethyl ether of diethylene glycol. Tower 28 can easily be operated so that the overhead contains less than 3% by weight of the tetramethyl lead production while the bottoms contains less than about 0.5% of the tetrahydrofuran.

In tower 28 the overhead vapors pass via vapor line 29 to condenser 31, where substantially all of the overhead components other than a portion of the methyl chloride and by-product methane gas are condensed. From condenser 31 the condensate and uncondensed gas pass via line 32 to overhead receiver 33, which supplies reflux to tower 28 via line 34, and recycle dry solvent to Grignard preparation tank 11 via line 36. Uncondensed material in overhead receiver 33 passes via vapor line 37 to refrigeration condenser 38 where methyl chloride is condensed and returned to receiver 33, while methane and other noncondensable gases are exhausted via line 39 to the atmosphere.

The bottoms from tower 28 contain more than 97% of the tetramethyl lead together with unreacted Grignard reagent, magnesium halide, less than about half of the benzene, and hexylethyl ether of diethylene glycol. This stream is transferred via line 41 to hydrolyzing tank 42, equipped with a stirrer 43 or other equivalent agitating device. Here a stream of aqueous hydrochloric acid, e.g., 3% by weight, is admitted via source 44 and line 46. The amount of hydrochloric acid added is stoichiometrically equivalent to the unreacted Grignard reagent, while the amount of water is at least that necessary to dissolve magnesium chloride formed by decomposition of the Grignard and that initially present as an etherate complex in the electrolytic reaction mixture.

From hydrolysis tank 42 the resultant mixture of aqueous magnesium chloride-containing phase and organic phase is pumped via line 47 to settling drum 48. Here the heavier aqueous phase is withdrawn via line 49 as a bottoms material, while the organic phase is taken overhead via line 51. The aqueous phase contains substantially less than a percent or so each of hexylethyl ether of diethylene glycol, benzene, and tetramethyl lead, and may be disposed of, advantageously after decomposition of the lead by chlorination.

The organic phase contains substantially all (except minor losses) of the tetramethyl lead, together with hexylethyl ether of diethylene glycol and aromatic hydro-

carbon. It is conducted via line 51 to distillation tower 52.

In the embodiment depicted in the drawing, distillation tower 52 is supplied with steam to effect separation of the tetramethyl lead (and benzene) from hexylethyl ether. Tower 52 may have, say, 3-8 theoretical plates and may operate at a pressure not substantially above atmospheric, e.g., 15 p.s.i.a., with reboiler temperature below about 110° C. and a reflux ratio of between about 1 and 5. Steam is admitted near the bottom via line 53, while the steam-tetramethyl lead-benzene overhead is passed via vapor line 54, condenser 56, and condensate line 57 to overhead receiver 58. The aqueous layer, consisting essentially of water with a small amount of dissolved benzene and tetramethyl lead, is taken from the upper portion of overhead receiver 58 and refluxed to the tower 52 via line 59, with the excess being discarded via line 61. Steam may be employed in amounts of between about 0.1 and 10 mols/mol feed.

The product of the inventive process is recovered via line 62. It is composed of tetramethyl lead, together with some—usually a minor amount—of benzene and a small amount of dissolved and/or entrained water. It may be dried before blending into motor or aviation mix according to well known techniques and recipes.

The bottoms from distillation tower 52 is composed almost entirely of the high boiling hexylethyl ether of diethylene glycol, with a small amount of water and tetramethyl lead being present. It is taken off via line 63, sent to settling drum 64 where the aqueous phase is removed via line 66 and the bulk of ether is transported via line 67 to drying tower 68. Tower 68, having, say, 1-5 theoretical plates and a reflux ratio in the range of about 1-5, and operating at a pressure of not substantially above atmospheric, e.g., 14.5 p.s.i.a. with the reboiler temperature of up to about 130° C., effectuates drying of the ether by fractional distillation. Water is taken overhead via line 69 (through a conventional reflux system, not shown), while the dried ether is conducted via line 71 to the electrolysis zone via Grignard preparation zone 11 and, optionally, via a solid desiccant 72 such as absorbent alumina or a molecular sieve.

As an alternate to the use of steam, tower 52 may be operated under vacuum in order to maintain the reboiler temperature below the desired maximum of about 110° C. For this operation, a subatmospheric pressure of, say, 300 millimeters' mercury absolute is imposed, and the overhead will consist of tetramethyl lead and benzene, while the bottoms will consist of hexylethyl ether of diethylene glycol with possibly a small amount of tetramethyl lead. For vacuum operation, overhead receiver 58 will have only a single phase therein, and accordingly aqueous product line 61 may be dispensed with. Similarly, there is no need for settling drum 64, drying tower 68, or desiccant 72, since the ether is recovered in a dry form, suitable for recycle to the electrolysis, and via line 70 to the first distillation in tower 28.

The final tetramethyl lead product is of high quality, water white, and is recovered in excellent yield. Thus it is apparent that there is provided, in accordance with the invention, an outstanding process for the commercial manufacture of tetraalkyl lead compounds.

While the invention has been described in conjunction with certain embodiments thereof, it will be evident that many alternatives, modifications and variations will occur to those skilled in the art in light of the foregoing exemplary description. It is intended to embrace all such

alternatives, modifications and variations as fall within the spirit and broad scope of the appended claims.

We claim:

1. A process for recovering a tetraalkyl lead product and solvent from the electrolytic reaction mixture obtained by electrolyzing an alkyl Grignard reagent with a lead anode in a solvent comprising excess alkyl halide, a high boiling ether, tetrahydrofuran, and an aromatic hydrocarbon, which process comprises: distilling said mixture to obtain an overhead containing excess alkyl halide, tetrahydrofuran, and aromatic hydrocarbon, together with a bottoms containing tetraalkyl lead product, unreacted Grignard reagent, magnesium halide, and said high boiling ether; recovering said overhead; hydrolyzing the bottoms with aqueous hydrochloric acid; separating the resulting aqueous phase containing magnesium halide from an organic phase containing tetraalkyl lead product and said high boiling ether; and distilling said organic phase to separate tetraalkyl lead product as an overhead from the high boiling ether as bottoms.
  2. Process of claim 1 wherein distillation of said electrolytic reaction mixture is effected at a pressure of below about 500 millimeters' mercury absolute and at a temperature of below about 110° C.
  3. Process of claim 1 wherein distillation of said organic phase is effected at subatmospheric pressure.
  4. Process of claim 1 wherein distillation of said organic phase is effected in the presence of steam, the resultant overhead is separated from water, and the resultant high boiling ether bottoms are redistilled to effect drying thereof.
  5. Process of claim 1 wherein said tetraalkyl lead product is tetramethyl lead.
  6. Process of claim 1 wherein said tetraalkyl lead product is tetraethyl lead.
  7. A process for recovering a tetraalkyl lead product and solvent from the electrolytic reaction mixture obtained by electrolyzing the corresponding alkyl Grignard reagent with a lead anode in a solvent comprising an excess of the corresponding alkyl halide, a dialkyl ether of an ethylene glycol having at least two carbon atoms in each alkyl group and not more than two ethylene groups in the glycol portion, tetrahydrofuran, and an aromatic hydrocarbon, which process comprises: distilling said mixture to obtain a dry overhead containing substantially all of the unreacted excess alkyl halide and tetrahydrofuran and at least a major portion of the aromatic hydrocarbon, together with a bottoms containing substantially all of the tetraalkyl lead product, unreacted Grignard reagent, magnesium halide, a minor portion of the aromatic hydrocarbon, and ether; recovering said overhead; hydrolyzing the bottoms with sufficient aqueous hydrochloric acid to dissolve the magnesium halide; separating the resulting aqueous phase containing magnesium halide from an organic phase containing tetraalkyl lead product, aromatic hydrocarbon, and ether; and distilling said organic phase to separate tetraalkyl lead and at least a portion of the aromatic hydrocarbon as an overhead from the ether bottoms.
